UNITED STATES PATENT OFFICE.

PAUL A. KNAPPE, OF SANTA ROSA, CALIFORNIA.

HAMMOCK.

Application filed July 17, 1926. Serial No. 123,130.

This invention relates to improvements in hammocks. It has particular reference to a hammock which may be adjusted to several positions.

5 The principal object of this invention is to produce a hammock wherein the user may employ the same as a bed, a reclining chair, or as a conventional hammock.

10 A further object is to produce a hammock of the character wherein the same parts are employed for accomplishing the various positions.

15 A further object is to produce a hammock which is simple to manipulate.

20 A still further object is to produce a hammock which is cheap to manufacture.

Other objects and advantages will be apparent during the course of the following description.

25 In the accompanying drawings forming a part of this specification, and in which like numerals are employed to designate like parts throughout the same,

Figure 1 is a side elevation of my hammock when employed as a reclining chair,

Figure 2 is a side elevation of my hammock when employed as a bed,

Figure 3 is a top plan view of Figure 1,

Figure 4 is a side elevation of my hammock when the same is used as a conventional hammock.

I am aware of the fact that many hammocks are adjustable so as to suit the requirements of different individuals. The 35 average hammock, however, is adjustable only to various standard hammock adjustments such as the raising or lowering of one end or the other, while with applicant's the same may be stretched so as to form a taut surface upon which a person may lie flat, or may be adjusted so as to form a reclining chair-like structure, if desired.

40 In the accompanying drawings wherein for the purpose of illustration is shown a preferred embodiment of my invention, numerals 5 and 6 designate supporting posts. It is obvious, however, that these supports may take any other form desirable.

45 At 7 I have shown fastening elements secured in the supports at which fastening element my hammock is adapted to be attached for the purpose of supporting the same in any desired position.

50 Referring now to Figure 1 the numeral 8 refers to a fabric strip having its opposite ends attached to cross bars 9 and 11. A

supporting rope is shown at 12 which supporting rope extends between the cross bar 9 and one of the fastening elements 7. A similar rope 13, secured to the cross bar 9, 60 normally hangs in the position shown in this figure. The same, however, may be moved to the dotted line of this figure and attached to one of the fastening elements 7 which act and serve to prevent the hammock from swinging. A rope 14 is attached to the cross piece 11 and to one of the fastening elements on the post 5. A strip 16 of fabric is secured to the fabric 8 in such a manner as to form a pocket 17. See Figures 70 2 and 4. Through its pocket a cross brace 18 is adapted to be placed which cross brace has rings 19 in each end thereof, the purpose of which will later be seen. A cross brace 21 is secured to the free end of the 75 fabric 16 and to this brace is attached a rope 22, which rope is adapted to be attached to one of the fastening elements upon the post 5. It will be noted that this cross brace 21 also carries rings in the end thereof of which are designated by the numeral 23, the purpose of which will be later seen.

80 When my hammock is used as a reclining chair as illustrated in Figures 1 and 3 I employ parallel braces 24 and 26, each of which is provided with a hooked extremity as shown in 27 and 28, respectively. In employing these parallel braces the same are passed through the rings 19 and 23 and the hooked ends are caused to engage the supporting rope 22. When in this position the portion 29 of the fabric 8 sags between the cross piece 11 and the cross piece 23, forming a foot section while portion 31 of the fabric 8 forms the back against which the individual leans. By varying the point of engagement of the rope 12 with the post 6 the angle of inclination of the back portion of 31 may be changed to accommodate the individual taste of the user, while if the user wishes the hammock rigid so that it will not move, the rope 13 and a similar rope shown in dotted line 32 are employed which ropes will prevent any movement of the 95 hammock.

100 When it is desired to use my hammock as a bed the parallel braces 24 and 26 are removed as well as the cross brace 18. At the same time the cross brace 21 and its attached fabric will drop to the position shown in Figure 2. By now securing the ropes 12 and 13, and 14 and 32 to their respective 105

110

fastening elements in the posts 5 and 6, the fabric 8 may be stretched taut so that it will form a proper bed support upon which an individual may lie.

5 When it is desired to use the hammock in the conventional manner the parts are arranged as shown in Figure 4, which arrangement is quite obvious from the previous description with the result that further 10 comment thereon is unnecessary.

It will thus be seen that I have devised a hammock which may be adjusted to the various positions above described and one which will accomplish all of the objects above set 15 forth.

It is to be understood that the form of 20 my invention herein shown and described is to be taken as a preferred example of the same, and that various changes in the shape, size and arrangement of parts may be resorted to without departing from the spirit 25 of the invention or the scope of the subjoined claims.

Having thus described my invention, I 25 claim:

1. In a hammock of the character described, comprising a fabric strip, cross pieces secured at the ends of said strip, supporting ropes attached to said cross pieces 30 and adapted to be secured to a suitable support, a second fabric strip secured to said first fabric strip in such a manner as to

form a pocket, a cross brace removably secured within said pocket, a cross brace secured at the free end of said last mentioned fabric strip, a supporting rope secured to said last mentioned cross brace and means for maintaining said cross brace in substantially parallel alignment, said means comprising a pair of spaced members having 40 sliding engagement with said cross braces and hooks secured in the ends of said parallel members, said hooks being adapted to engage said rope secured to said cross brace carried on the free end of said fabric strip. 45

2. In a hammock a fabric strip, a cross piece secured to each end of said fabric strip, rope securing means extended between said cross pieces for a suitable support, a second fabric strip secured to said first fabric strip in such a manner as to form a pocket, a cross brace adapted to a removable position in said pocket, a second cross brace secured to said second mentioned fabric strip, a rope extending between said last mentioned cross brace and said supporting means, parallel members adjustably secured to said cross braces, hooks secured in the one end of each of said parallel members and adapted to engage said supporting rope, and means for snubbing said hammock for the purpose specified. 55

In testimony whereof I affix my signature.
PAUL A. KNAPPE.
